Bamert Regan PLLC

(57) **CLAIM**

I claim the ornamental design for a charging handle, as shown and described.

DESCRIPTION

FIG. 1 is right isometric perspective view of a first embodiment of a charging handle, showing my new design.

FIG. 2 is a left isometric perspective view thereof.

FIG. 3 is a left isometric perspective view thereof.

FIG. 4 is a right isometric perspective view thereof.

FIG. 5 is top plan view thereof.

FIG. 6 is bottom plan view thereof.

FIG. 7 is a rear elevational view thereof.

FIG. 8 is a right side elevational view thereof.

FIG. 9 is a front elevational view thereof.

FIG. 10 is left side elevational view thereof.

FIG. 11 is right isometric perspective view of a second embodiment of a charging handle, showing my new design.

FIG. 12 is a left isometric perspective view thereof.

FIG. 13 is a left isometric perspective view thereof.

FIG. 14 is a right isometric perspective view thereof.

FIG. 15 is top plan view thereof.

FIG. 16 is bottom plan view thereof.

FIG. 17 is a rear elevational view thereof.

FIG. 18 is a right side elevational view thereof.

FIG. 19 is a front elevational view thereof.

FIG. 20 is left side elevational view thereof.

FIG. 21 is right isometric perspective view of a third embodiment of a charging handle, showing my new design.

FIG. 22 is a left isometric perspective view thereof.

FIG. 23 is a left isometric perspective view thereof.

FIG. 24 is a right isometric perspective view thereof.

FIG. 25 is top plan view thereof.

FIG. 26 is bottom plan view thereof.

FIG. 27 is a rear elevational view thereof.

FIG. 28 is a right side elevational view thereof.

FIG. 29 is a front elevational view thereof.

FIG. 30 is left side elevational view thereof.

FIG. 31 is right isometric perspective view of a fourth embodiment of a charging handle, showing my new design.

FIG. 32 is a left isometric perspective view thereof.

FIG. 33 is a left isometric perspective view thereof.

FIG. 34 is a right isometric perspective view thereof.

FIG. 35 is top plan view thereof.

FIG. 36 is bottom plan view thereof.

FIG. 37 is a rear elevational view thereof.

FIG. 38 is a right side elevational view thereof.

FIG. 39 is a front elevational view thereof; and,

FIG. 40 is left side elevational view thereof.
